O. JAEGER.

COIN RECEIVING DEVICE.

APPLICATION FILED MAR. 23, 1917.

1,257,870.

Patented Feb. 26, 1918.

UNITED STATES PATENT OFFICE.

OTTO JAEGER, OF ELKINS PARK, PENNSYLVANIA, ASSIGNOR TO HARRY S. KELSEY, OF BOSTON, MASSACHUSETTS.

COIN-RECEIVING DEVICE.

1,257,870.

Specification of Letters Patent. Patented Feb. 26, 1918.

Application filed March 23, 1917. Serial No. 156,839.

To all whom it may concern:

Be it known that I, OTTO JAEGER, a citizen of the United States, and a resident of Elkins Park, county of Montgomery, and 5 State of Pennsylvania, have invented certain new and useful Improvements in Coin-Receiving Devices, of which the following is a full, clear, and exact disclosure, reference being had to the accompanying drawings, forming a part of this specification.

My invention relates to improvements in coin receiving devices particularly adapted for use in connection with machines used in lunch rooms and restaurants for vending or 15 dispensing food and known as "special order" machines. Machines of this character are used in places where the attendant of the machine is screened from the customer by a suitable wall having a coin slot therein 20 for the reception of the coin or coins in payment for the special order, and where the attendant, upon the receipt of the order, delivers to the customer, through a suitable opening in the wall, a suitable key to be used 25 by the customer to open a suitable device to obtain the food after the order has been filled.

The object of my invention is to provide a coin receiving device of novel, simple and 30 efficient construction adapted to receive a coin or coins from the customer and conduct or guide the coin or coins to a suitable closed receptacle, and having provision, firstly, whereby the coin or coins may not 35 be removed from the device by the attendant receiving the order, secondly, whereby the movement of the coin or coins through the device to the receptacle is temporarily arrested, thirdly, whereby the attendant may 40 view the temporarily arrested coin or coins to see that they are correct and to thereby receive the "special order," and, fourthly, whereby the attendant may, by moving a part of the device by hand, release the temporarily arrested coin or coins and thereby 45 permit them to pass into the receptacle.

With this object in view, my invention consists in the novel construction and combinations of parts hereinafter described and 50 claimed.

In the accompanying drawings, illustrating my invention,

Figure 1 is a vertical section of a frame

structure provided with a coin receiving device embodying my invention.

55

Fig. 2 is a plan view of the coin guide and the upper portion of the coin receptacle.

Fig. 3 is a vertical section through the coin guide and its transparent panel, on line 60 3-3 of Fig. 4.

Fig. 4 is a vertical section through the upper portion of the coin receptacle and the adjacent end of the coin guide.

Fig. 5 is a vertical section through the upper portion of the receptacle, on line 5-5 65 of Fig. 4.

Fig. 6 is a transverse section through the coin guide, on line 6-6 of Fig. 1.

Referring to the drawings, 2 designates a frame structure which may be of any form 70 and size for its intended purpose. The frame structure 2 includes a partition wall 4 adapted to separate the customer from the attendant of the machine. The wall 4 is provided with a coin slot 7 into which the coin 75 or coins are inserted by the customer from a position in front of the wall 4.

Extending downwardly from the slot 7 is a coin guide 8 which is inclined, as shown, and which is adapted to receive the coins 80 inserted into the slot 7. The coin guide 8 comprises a bottom wall 9, side walls 10, extending upwardly from the sides of the bottom wall 9, and flanges 11 extending inwardly from the top of the side walls 10. 85 The space between the side walls 10 is slightly greater than the diameter of the coins to be inserted into the slot 7 and the space between the bottom wall 9 and the flanges 11 is slightly greater than the thickness of the said coins, the walls 9 and 10 and flanges 11 being so related to each other as to permit the coins inserted into the slot 7 to descend freely by gravity through the guide 8 and to prevent the removal of the 90 coins from the guide 8 after they leave the slot 7.

The coin guide 8 extends from the slot 7 to a closed coin receptacle 12 having a slot or opening 13 therein in registry with the lower end of the guide 8, whereby coins descending through the guide 8 may enter the receptacle 12 through the slot or opening 13. The upper end of the coin guide 8 is secured to a bracket 14 which is secured 100 to the wall 4; and the lower end of the guide 105

8 is secured to the receptacle 12 by means of a bracket 15 which embraces the guide 8 and the receptacle 12 and which is secured thereto by suitable screws.

5 The ends of the flanges 11 of the coin guide 8 adjacent to the receptacle 12 are cut away to expose to view the full face or faces of one or more coins when they reach positions adjacent to the receptacle 12 as they 10 descend through the guide 8. The lower end portion of the guide 8 where the flanges 11 are cut away to expose the coins is covered by a transparent panel 16 of glass or other suitable material through which the coins 15 may be seen and which rests upon the guide 8. The panel is contained within grooves in a suitable frame 17. The frame 17 is provided with a bracket 18 which extends downwardly therefrom and around the bottom of 20 the guide 8 and has its respective ends attached to the sides of the frame 17, thereby inclosing the guide 8 between the bracket 18 and the frame 17 and panel 16. The frame 17 and its panel 16 are secured to the guide 25 8 by a thumb screw 19 screwed into and through the bracket 18 and engaging the bottom of the guide 8.

The receptacle 12 is provided with a coin arresting member 20 adjacent to the lower 30 end of the coin guide 8 and comprising a part or arm 21 located within the receptacle 12, an arm 22 located outside the receptacle 12 and a pivot shaft 23 extending through the wall of the receptacle 12 and to which the arms 21 and 22 are secured. The arm 22 is provided with a pin 24 which extends therefrom adjacent to one side of the receptacle 12 and rests against the same when the member 20 is resting in its normal position 35 shown in full lines in the drawings. In this normal position of the member 20, the part or arm 21 of the member extends upwardly and bars the opening 13 connecting the guide 8 with the receptacle 12 and arrests the downward movement of the coins 40 within the guide 8 before they enter the receptacle and retains the coins in the lower portion of the guide 8 beneath the transparent panel 16. When the attendant raises the arm 22 and thereby moves the member 20 on its pivot 23 to the position shown by dotted lines in Fig. 5, the part or arm 21 is moved 45 away from the opening 13, thereby releasing the coins within the guide 8 and permitting 50 them to descend by gravity and into the receptacle 12.

The coin receptacle 12 may be of any suitable construction. As herein shown it comprises a lower box-like portion 25 suitably 55 secured to the frame structure 2 and having an upwardly extending reduced portion 26 to which the lower end of the coin guide 8 is attached, as previously described. When the coins are received into the upper end of the 60 reduced portion 26 they fall down into the

box-like portion 25 which is provided with a hinged door 27 which may be normally locked in the closed position shown in the drawings and which may be opened to permit the removal of the accumulated coins 70 therein.

The operation of the device, briefly described, is as follows:

The customer in front of the wall 4 inserts the coin or coins which represent the 75 purchase price of the "special order" into the slot 7, and the coin or coins thus inserted descend by gravity through the coin guide 8 until the downward movement of the coin or coins, indicated at C, is arrested beneath 80 the transparent panel 16 by the part or arm 21. The attendant back of the wall 4 sees through the glass panel 16 that the inserted coin or coins are correct and thereby receives the "special order" and thereafter 85 raises the arm 22 and permits the coin or coins to pass into the receptacle 12. The attendant then releases the arm 22 and the member 20 automatically returns to its normal position for a succeeding operation. It 90 will thus be seen that the said attendant can not remove the coins from the device and that they can only be removed from the receptacle by the proper person provided with a key to unlock the door 27.

I claim:

1. In a device of the character described, the combination of a frame structure having a coin slot therein, a downwardly inclined coin guide extending from said slot and adapted to receive coins therefrom and guide them in their downward movement by gravity, said guide preventing the removal of coins therefrom and having an opening therein through which coins may be seen, a substantially vertically-arranged receptacle extending downwardly from the lower end of said guide and adapted to receive coins therefrom, a shaft mounted to turn in a wall of said receptacle, an arm secured on the inner end of said shaft, and means on the outer end of said shaft to hold said arm normally in a position obstructing the lower end of said guide and preventing coins from passing from the open end of said guide and into said receptacle, said means being operative to move said arm from its obstructing position.

2. In a device of the character described, the combination of a frame having a coin slot therein, a downwardly inclined guide extending from said slot and adapted to receive coins therefrom and guide them in their downward movement by gravity, said guide preventing the removal of coins therefrom and having an opening therein through which coins may be seen, a substantially vertically-arranged receptacle extending downwardly from the lower end of said guide and adapted to receive coins therefrom, a shaft 120

mounted to turn in a wall of said receptacle, an arm secured on the inner end of said shaft, and an arm secured on the outer end of said shaft and having a part resting normally against a part of said receptacle and holding the first named arm in a position obstructing the lower end of said guide and preventing coins from passing from the open

end of said guide and into said receptacle, the second named arm being operative to move the first named arm from its obstructing position.

In witness whereof, I have hereunto set my hand this 19th day of March, 1917.

OTTO JAEGER.
